UNITED STATES PATENT OFFICE.

FRED RICHARD SKINNER, OF SYRACUSE, NEW YORK.

DESIGN FOR A PUZZLE BOX OR CASE.

SPECIFICATION forming part of Design No. 31,265, dated July 18, 1899.

Application filed June 13, 1899. Serial No. 720,409. Term of patent 14 years.

To all whom it may concern:

Be it known that I, FRED RICHARD SKINNER, a citizen of the United States, residing at Syracuse, in the county of Onondaga and State of New York, have invented and produced a new and original Design for Puzzle Boxes or Cases, of which the following is a specification, reference being had to the accompanying drawings, forming part thereof, in which—

Figure 1 is a plan view of my newly-designed puzzle-box; Fig. 2, a section on the line 2 2 of Fig. 1, and Fig. 3 a section on the line 3 3 of Fig. 1.

As shown in the drawings, the leading or material feature of my design consists of a rectangular box or casing composed of a bottom 5 and vertical side walls 6, said box or casing being substantially square in form, and being also open at the top and provided with a horizontal partition 7, in the upper surface of which are formed parallel grooves 8, 9, 10, 11, 12, and 13 and similar grooves 14, 15, 16, 17, 18, and 19, which cross the first-named grooves at right angles. The grooves 15 and 16 are interrupted, and consist of two separate sections which do not extend across the middle of the partition 7.

At each corner of the box or casing the partition 7 is provided with a circular opening 20, with which the grooves 8 and 13 and 14 and 19 communicate, and the groove 19 is provided with a corresponding circular opening 21 centrally thereof, the groove 18 with two similar openings 22 at each side of the

middle thereof, the groove 17 with similar openings 23, and the separate sections of the grooves 15 and 16 at their inner ends communicate with similar openings 24.

At the middle of the groove 8 is a corresponding opening 25, and at each side of the middle of the groove 9 is a similar opening 26, while the grooves 10 and 11 are provided between the grooves 17 and 18 with similar openings 27, and the groove 12 at each side of the middle with a similar opening 28, and the groove 13, centrally thereof, with a similar opening 29. The right-hand section of the groove 15 is also provided with an opening 30, and in the central portion of the groove 14 is an oblong opening 31. The transverse and intersecting grooves communicate with said openings, as shown, and below the oblong opening 31 is an inclined plate 32, which is grooved on its upper side, as shown at 33, and the upper end of the groove in said plate communicates with the groove 14.

Having fully described my invention, I claim as new and desire to secure by Letters Patent—

The design for a puzzle box or case herein shown and described.

In testimony that I claim the foregoing as my invention I have signed my name, in presence of the subscribing witnesses, this 9th day of June, 1899.

FRED RICHARD SKINNER.
